ATTORNEY

Levi J. Evans
WITNESS:

UNITED STATES PATENT OFFICE

ENOCH M. REEVES, OF FLINT, MICHIGAN

STRIPING PENCIL FOR AUTOMOBILES

Application filed August 1, 1927. Serial No. 209,983.

The object of this invention is the provision of a guide for a striping brush of the fountain type employed by painters for painting lines on automobiles and the like and in which the said guide provides a means for accurately directing the brush over the part to be painted or striped and further whereby spaced parallel lines may be likewise accurately painted or further whereby lines of different thicknesses may be also accurately painted.

For a full understanding of the invention and the merits thereof, reference is to be had to the accompanying drawings which form part of this specification, and wherein:

Figure 1 is a side elevation illustrating the improvement in use.

Figure 2 is a top plan view of the improvement.

Figure 3 is a sectional view approximately on the line 3—3 of Figure 2.

Figure 4 is a fragmentary plan view illustrating the brush provided with a substantially V-shaped nozzle in counterdistinction to the flat and substantially rectangular nozzles disclosed by the remaining figures of the drawing.

In the drawings, the numeral 1 designates a fountain brush of the type employed by painters in painting lines of the character commonly known in the trade as striping. The barrel of the brush 1 has a flat offset nozzle portion 2 and an air inlet opening 3, adjacent to said nozzle portion. The second and open end of the brush has secured thereon a compressible rubber nipple 4.

The improvement contemplates the employment of a metal member which is slotted from one of its ends to provide a two-arm spring and the arms of this spring are designed to exert a pressure toward each other. The inner arm 5 of the spring 6 is of a less length than the outer arm 7. The inner arm 5 may be integrally formed with split ring clamps 8 for frictionally engaging with the barrel of the brush 1, and for likewise holding the spring 6 longitudinally adjusted on the barrel. By reference to the drawings, and especially Figure 3 thereof, it will be seen that the outer face of the arm 5 is form-

ed with spaced thickened portions which are centrally concaved, as at 8' and the ends of these thickened portions are formed with split ring clamps 8. This arrangement materially strengthens the arm 5 or the portions thereof provided with the split clamps. The outer and longer arm 7 of the spring 6 has a spherical end 9 designed, as illustrated by Figure 1 of the drawings, to contact with a bead or like projection on the body of an automobile or the like, so that the nozzle end 2 of the brush will be accurately guided when drawing or striping a line on the vehicle or like body. Threaded through the arm 7 of the spring 6 and having its inner rounded end received in a depression on the arm 5 there is a screw 10 that has an outer headed portion 11. By adjusting the screw the arm 7 may be brought toward or away from the brush 1 and likewise by adjusting the screw 10 parallel lines may be striped on the body to be decorated. By drawing these lines close together so that the same intersect each other, comparatively wide lines may be painted as will, it is thought, be readily understood.

By arranging the brush and the guide at an angle of approximately 30 degrees, as disclosed by Figure 1 of the drawings the paint from the barrel of the brush will be automatically fed through the nozzle thereof so that the nipple 4 need not be compressed to force such paint through the nozzle. However, by reference to the drawings it will be seen that the end 6 of the improvement contacts with the compressible nipple 4 of the fountain brush 1 and should the paint become clogged in the brush head or should it be found desirable that the same be forced through the said brush, so that all of the paint in the brush will be ejected through the nozzle 2 the operator whose fingers contact with the bulb or nipple 4 and with the end 6 of the improvement can readily compress the said bulb or nipple.

The improvement is of a simple construction and may be attached to fountain brushes of the ordinary type. The clamps 8 as previously stated, permit of the guides being longitudinally adjusted on the brush, so that

the spherical guide end 9 of the improvement may be properly positioned to engage with the bead or with other guiding surfaces on the vehicle or like body to be striped.

5 In Figure 4 the construction is substantially similar to that previously disclosed, except that the barrel of the brush is formed with a pointed or substantially V-shaped nozzle 12.

10 Having described the invention, I claim:—

A guide for striping pencils, comprising an elongated metal member slotted longitudinally from one of its ends to afford two spring arms, and one of the arms being of a greater length than the other arm, the shorter arm at spaced intervals, having its outer face thickened and concaved and the corners of the said thickened portions formed with curved spring gripping fingers to engage with a striping pencil, and a headed element having a shank which is threaded through the longer arm and contacting with the shorter arm at a point opposite the outer thickened portion of said shorter end.

15 In testimony whereof I affix my signature.

ENOCH M. REEVES.
